UNITED STATES PATENT OFFICE.

JOSEPH GERCHGALL, OF CHICAGO, ILLINOIS.

DESIGN FOR A FLOOR LAMP.

61,412.

Specification for Design.

Patented Aug. 29, 1922.

Application filed January 6, 1922. Serial No. 69. Term of patent 14 years.

To all whom it may concern:

Be it known that I, JOSEPH GERCHGALL, a citizen of the United States, residing at Chicago, in the county of Cook and State of Illinois, have invented a new, original, and ornamental Design for Floor Lamps, of which the following is a specification, reference being had to the accompanying drawings, forming part thereof.

The figure is a view of a floor lamp showing my new design.

I claim:

The ornamental design for a floor lamp as shown.

JOSEPH GERCHGALL.
